UNITED STATES PATENT OFFICE

160,568

SET OF GAME PIECES

Luis Abbadié (Brizuela), Guadalajara, Mexico, assignor of fifty per cent to Salvador García
(Ibarra) of Jiquilpan, Michoacan, Mexico

Application December 21, 1948, Serial No. 150,296

Term of patent 14 years

(Cl. D34—5)

To all whom it may concern:

Be it known that I, Luis Abbadié (Brizuela), a citizen of Mexico, residing at Guadalajara, Jalisco, Mexico, have invented a new, original, and ornamental Design for a Set of Game Pieces, of which the following is a specification, reference being had to the accompanying drawing, forming part thereof.

Figure 1 is a plan view of twenty-nine of a set of game pieces, showing my new design, and Figure 2 is a plan view of the remaining game pieces of said set.

The game pieces are substantially flat and thin, and the under surfaces thereof are plain.

The drawings are shaded to indicate contrast in color.

The dominant features of my new design are shown in solid lines in the drawings.

The set of game pieces comprises sixty-two game pieces.

I claim:

The ornamental design for a set of game pieces, as shown and described.

LUIS ABBADIÉ (BRIZUELA).
